SHIFT CONTROL FOR TELEGRAPH
PRINTERS

Robert F. Dirkes, Jamaica, N. Y., assignor to The
Western Union Telegraph Company, New
York, N. Y., a corporation of New York

Application September 2, 1932, Serial No. 631,563

10 Claims. (Cl. 178—33)

This invention relates to a printing telegraph system and more particularly to a method of and apparatus for controlling the shift mechanism of a receiving printer.

5 In printing telegraph systems used in certain types of service, particularly quotations involving the price of various stocks, commodities, etc., it is necessary to print in both upper and lower case positions and to change from one case to the other frequently, that is, every few characters. Heretofore three general schemes have been used for this purpose. The first involves the use of a five unit permutation code giving thirty-two distinct combinations, two of which are employed 10 to operate the shift mechanism to either upper or lower position, thereby enabling substantially twice this number of characters to be printed. The shift mechanism is locked in each shifted position until the opposite shift combination is received. This system has the advantage of employing only a five unit code but where case shifts occur frequently considerable line time is lost in transmitting the shift and unshift combinations.

15 The second scheme involves the addition of a case shift impulse to each code combination, the added impulse serving to operate the shift mechanism to the proper case position as each code combination is received. This latter scheme, while a considerable improvement on the first 20 method has the disadvantage that the characters are equally divided between lower and upper case position. Since the upper and lower case characters are printed on different levels on the ticker tape, the former comprising the letters of the alphabet and certain added symbols and the latter the numerals and fractions, it would be more advantageous in certain instances if the 25 number of characters in the letter or lower case position could be increased beyond the available thirty two. On the other hand the entire thirty two characters are not required in the numerals or upper case position.

30 The third method of upper and lower case control overcomes this difficulty by using a jumbled six unit code giving sixty two distinct combinations, each of which selects an individual type bar, no shift mechanism being employed. The disadvantage of this latter scheme is that it complicates the printing mechanism by doubling the 35 number of type bars, pull bars, etc., in the ticker, thereby rendering the machine expensive and more difficult to obtain properly aligned printing.

35 The present invention has for its object to produce a new shift control in which either equal or

unequal distribution of characters in either shift position may be obtained.

Another object is to provide a method of and apparatus for controlling the shift mechanism of the telegraph printer by predetermined sub-combinations or impulses used in each character code.

40 A still further object is to provide a method of and means for controlling two separate selectable elements of a printer by a single code combination and a sub-combination occurring therein.

Other objects and advantages of the invention will hereinafter appear.

45 In accordance with my invention I employ a six unit code giving sixty-four distinct combinations and I utilize certain sub-combinations occurring in the main combinations to control the shift mechanism and any other auxiliary mechanism of the printer. For instance, in the embodiment described hereinafter, I have utilized all combinations in which the 3rd and 4th impulses or the 4th and 5th impulses are both marking for characters occurring in the upper case 50 position and the remaining combination or characters occurring in the lower case position. This gives a distribution of twenty four upper case characters and forty lower case characters. By choosing other controlling sub-combinations different distributions of the upper and lower case characters can be obtained.

55 The invention will best be understood by reference to the accompanying drawing in which

Figure 1 shows an exemplary arrangement of the marking and spacing impulses of the letters and figures code combinations;

Figure 2 is a vertical sectional view of a receiving printer embodying the present invention;

Figure 3 is a fragmentary plan view of the printer; and

Figure 4 is a diagram showing a possible arrangement of the code bars of the receiving printer.

60 Referring first to Figure 1, I have shown in the left hand column the code combinations used for the letters or lower case characters, and in the right hand column the figures or upper case character combinations. The blank spaces represent spacing impulses and the numerals represent the numbers of the marking impulses of each combination. It will be noted that each of the figures or upper case combinations employs either the 3rd and 4th impulses marking or the 4th and 5th impulses marking, whereas in the

letters or lower case combinations these sequences of marking impulses do not occur.

The shift mechanism of the receiving printer to be presently described in connection with Figures 1 and 2 is arranged to respond whenever the 3rd and 4th or 4th and 5th impulses are marking to actuate the printing mechanism to upper case position and when neither of these sub-combinations occurs to retain it in lower case position.

Referring to Figures 2 and 3, 10 designates the code bars of a receiving printer, six of which are provided, notched so that for every code combination a single row of notches in the six bars 15 will be aligned. A group of type bars 11 (one only being shown) are pivoted on an arcuate rod 12 and normally rest in a vertical position against an arcuate pad 13. The type bars strike downwardly against the tape (not shown) arranged to 20 pass from right to left horizontally across the revolving platen 14. Each type bar may carry a lower case character 15 and an upper case character 16. The type bars are provided with individual pull bars 17, having a rack 18 engaging a 25 pinion 19 on the type bar. The pull bars are held against the edges of the code bars 10 by individual springs 20, but are normally prevented from entering the notches of the code bars by the staggered or unaligned relation thereof. In each 30 position of the code bars, however, as stated, one row of notches will be in alignment, permitting one of the pull bars to move inwardly so as to bring the shoulder 21 thereof into the path of a reciprocating bail 22, so as to be engaged thereby 35 to move the pull bar upwardly and thus throw the type bar against the paper.

The platen 14 comprises a roller mounted upon a horizontal shaft 23 and arranged to be shifted longitudinally thereof so as to rest beneath either 40 the upper or lower case character to permit printing from one or the other of these characters. The tape ordinarily remains stationary so that the lower case characters are printed adjacent one edge thereof and the upper case characters 45 adjacent the other edge.

The printing mechanism so far described is well known in the art and therefore has not been illustrated in detail.

The platen 14 is carried by a U-shaped frame 50 24 guided on a pin 25 and normally held in the lower or letters case position by a spring 26. It is adapted to be shifted towards the front of the machine by a U-shaped bell crank lever 27 pivoted on posts 28, 29 and having a vertical arm 31 engaging a rearward extension 32 of the frame 55 24. The lever 27 is actuated by one or both of two shift bars, 35, 36 having hooked lower ends 37 extending beneath one end 38 of the lever 27. The upper ends of the shift bars 35, 36 rest against the code bars 10, shift bar 35 being arranged to enter the aligned notches of the code bars whenever the 4th and 5th impulses of any code combination are marking and shift bar 36 similarly entering the aligned notches whenever the 3rd and 60 4th impulses are marking. Whenever one of the shift bars is so selected the shoulder 21 thereof is brought into the path of the bail 22, thereby being raised to effect the platen shift. This occurs simultaneously with the operation of one of the type bars and determines the case shift position in which printing occurs. At the end of each printing stroke, as the bail 22 moves downwardly, the platen is released and moved backward to lower case position by the spring 26.

If the code combination being received does not contain either the 3rd and 4th or 4th and 5th impulses marking, the notches opposite the shift bars 35 and 36 are not aligned and the platen remains in the unshift or lower case position.

Referring now to Figure 4 in which I have shown diagrammatically the arrangement of the notches in the code bars relative to the shift bars 35, 36 and the pull bars 17, it will be noted that in a position shown with all of the code bars in their normal or left hand position, the notches (represented by the dark portions of the bars) are not in line beneath either of the shift bars 35 and 36. However, if the 3rd and 4th code bars are shifted to the right, the notches will be aligned beneath the bar 36 and if the 4th and 5th code bars are shifted to the right the notches will be aligned beneath the shift bar 35. Consequently, any code combination involving either of these sequences of marking impulses will actuate the shift mechanism to the upper case position.

Referring back to the code shown in Figure 1, the letters and figures characters shown in the same horizontal row are carried by the same type bar as, for instance, the characters A and 1, B and 2, etc. Consequently, it is necessary that each type bar carrying two such characters must be selected by two entirely distinct code combinations. If the type bars are designated for convenience by the lower case character carried thereby, the A type bar will be selected by either the 1, 2, 3 marking combination or by the 1, 2, 3, 4 marking combination. This is readily accomplished by proper arrangement of the notches or code bars. By reference to Figure 4 again, it will be noted that if either the 1st, 2nd and 3rd or the 1st, 2nd, 3rd and 4th code bars are shifted to the right, notches will be aligned beneath the A code bar. In the first case, however, the notches will not be aligned beneath either of the 40 shift bars 35, 36 so that printing will occur only in the lower case position. Whereas in the second case, the shift bar 36 will be operated to effect printing in the figures case position. Similarly, the D type bar may be selected by transmitting either 1, 3, 6 marking combination or the 1, 3, 4, 6 marking combination, the former leaving the shift mechanism unoperated and the latter causing operation thereof to the figures position.

Others of the type bars, for instance, the Y bar and the bars corresponding to the remaining combinations listed therebelow in Figure 1 contain but a single character and, therefore, must be selected by a single combination. Referring again to Figure 4, if the Y selection comprising 1, 2 and 6 impulses marking is received, the notches will be aligned beneath the Y pull bar, but this will occur for no other combination.

It will be noted, therefore, that while certain of the type bars are selected by either of two combinations, others are selected by only a single combination.

While in the particular embodiment shown the 3rd and 4th or 4th and 5th marking impulses are used to control the shift mechanism, it is obvious that any other suitable combination of impulses may be used, as for instance, the 1st and 2nd, and the 2nd and 3rd to obtain the distribution of 40 70 characters in the lower case position and 24 in the upper case. If a different distribution is desired other combinations may be utilized. The following chart gives a number of sub-combinations of elements by which various other distributions 75

of upper and lower case characters may be obtained.

5	Number of characters in upper case	Number of characters in lower case	Sequence of marking impulses
	32	32	2, 3, 3, 4 or 4, 5
	28	36	1, 2 or 3, 4
	24	40	3, 4 or 4, 5
10	20	44	1, 2, 3 or 3, 4
	16	48	3, 4
	14	50	1, 2, 3 or 3, 4, 5

In the case of equal division of upper and lower case characters, 32 in each case, three shift bars would be required, one for the 2nd and 3rd marking sequence, one for the 3rd and 4th marking sequence and for the 4th and 5th marking sequence. In the distribution of 16 lower case and 48 upper case characters a single shift bar would be required and in the remaining distributions, two shift bars are needed. Other distributions may be obtained by selecting the proper controlling sub-combinations of the main code groups.

25 While this arrangement of sub-combinations of certain impulses has been described herein as controlling a case shift mechanism in a printer, it is understood that it can be as readily adaptable to control some other function of 30 mechanism within a printer. Such functions, for example, might be extra spacing of the tape when certain characters are printed, causing various switching functions to be operated upon receipt of code combinations for certain characters or control of line feed or carriage return 35 functions by certain sub-combinations of the received code impulses. In other words, the application of this selecting principle is not limited to case shift control, but is applicable to 40 control of any other mechanical or electrical function which can take place in the printer while the complete code combination is performing its work.

I have shown the platen as normally returning 45 to lower or letters case position following each selection. It is evident, however, that it might be locked in upper case position when so actuated and returned to lower case shift position by one or more separate shift pull bars selected whenever the 3rd and 4th or 4th and 5th impulses are 50 not marking. This mechanism is shown in dotted lines in Figures 3 and 4 and comprises a pair of unshift pull bars 41, 42 controlled by the opposite ends of the code disk 10 from the shift pull bars 55 35, 36. The pull bars 41, 42 operate a lever 33 which operates the bell crank lever 27 in the opposite direction from that produced by the shift pull bars 35, 36. The shift bars 41, 42, as an inspection of Figure 4 will show, are arranged to 60 enter aligned notches in the code bars whenever the 3rd and 4th or 4th and 5th code bars remain unshifted.

While the invention has been illustrated particularly with reference to type bar printers, it 65 is obvious, of course, that it is equally applicable to type wheel or other types of printers using upper and lower case positions. Therefore, I do not desire to be limited to the specific details shown and described herein but contemplate all 70 such modifications and variations thereof as will occur to those skilled in the art, as coming within the scope of the appended claims.

What I claim is:

1. In a telegraph printer, a printing mechanism, 75 a selecting mechanism, a case shift mechanism,

means responsive to a code combination for selecting said printing mechanism and means responsive to any one of a plurality of predetermined sub-combinations of two or more impulses occurring in said combination for controlling said case shift mechanism. 5

2. In a telegraph printer, a plurality of code bars, a plurality of character controlling pull bars, a plurality of shift pull bars, and a plurality of unshift pull bars, said code elements being 10 notched so as to select a predetermined character controlling pull bar in a plurality of positionings thereof and to select said case shift pull bar in one only of said plurality of positionings, and case shift mechanism actuated by said case shift pull 15 bar.

3. In a telegraph printer, a printing mechanism, mechanisms for accomplishing other functions, means responsive to a complete code combination of marking and spacing conditions for selecting 20 a particular character for printing, and means controlled by any one of a plurality of sub-combinations of two or more like conditions of said complete combination for effecting operation of 25 one of said function mechanisms.

4. A printing mechanism comprising a plurality of type bars greater in number than 32, each of which carries a character in the same case position and of which less than 32 also carry a character in a different case position, a plurality of actuating bars controlling said type bars, a paper feed mechanism co-acting with said type bars, a platen moveable independently of said paper feed mechanism to determine the character on a selected type bar to be printed, and a selecting mechanism responsive to six unit permutation code signals for simultaneously controlling 30 said type bars and said platen.

5. A printing telegraph receiver comprising a plurality of character carrying elements greater 40 in number than 32, provided with a nonshift character, a number thereof less than 32 also being provided with a shift character, a printing mechanism arranged to co-act with either of said characters on said character elements, means responsive to a six unit code combination of received 45 impulses for selecting one of said character elements and for operating said printing mechanism to co-act with either the shift or nonshift character. 50

6. A printing telegraph receiver comprising a plurality of character carrying elements greater in number than 32, a shift mechanism and permutation means on said receiver responsive to six unit code combinations of impulses for simultaneously selecting any one of said character elements and operating said shift mechanism. 55

7. In a type bar printer, a tape, a plurality of type bars, characters on said type bars, the type bars being greater in number than 32 but less in number than the number of characters, means responsive to receive six unit code combinations of impulse conditions for selectively operating said type bars to print on said tape and means whereby certain of the characters printed on said tape are transversely offset with relation to each other. 60

8. In a printing telegraph receiver, a plurality of type bars having "letters" and "figures" case characters, the "letters" case characters being 70 greater in number than 32 and the "figures" case characters being less in number than 32 and arranged on the same type bar with certain of said "letter" case characters and means whereby the "letters" case characters are printed in one line 75

and the "figures" case characters are printed in another offset line.

9. In a printing telegraph receiver, a plurality of character elements, a plurality of permutation members responsive to code combinations of impulses for selecting one of said character elements, a plurality of additional members each arranged to respond to a different impulse of each of said code combinations of impulses, a shift mechanism and a member operated by said additional members when operated singly or together for moving said shift mechanism.

10. In a printing telegraph receiver, a plurality of character selecting elements greater in number

than 32, a first character corresponding to each of said elements, a second character corresponding to predetermined ones of said elements, means responsive to a six unit permutation code combination of impulses for choosing one of said character selecting elements, and means also responsive to said permutation code combination of impulses and acting when the chosen character selecting element has more than one character corresponding thereto, for selecting for printing either the first or second character corresponding to the chosen character selecting element.

ROBERT F. DIRKES.
